UNITED STATES PATENT OFFICE

100,731

DESIGN FOR A TABLE

John H. Jewett, Detroit, Mich.

Application May 18, 1936, Serial No. 62,708

Term of patent 7 years

To all whom it may concern:

Be it known that I, John H. Jewett, a naturalized citizen of the United States, residing at Detroit, in the county of Wayne and State of Michigan, have invented a new, original, and ornamental Design for a Table, of which the following is a specification, reference being had to the accompanying drawing, forming part thereof.

The drawing is a perspective view of the article showing my new design.

I claim:

The ornamental design for a table as shown.
In testimony whereof I hereunto affix my signature.

JOHN H. JEWETT.
